WIRE BELT

Noah S. Harter, Waukegan, Ill., assignor to Cyclone Fence Company, a corporation of New Jersey

Application February 21, 1936, Serial No. 65,158

3 Claims. (Cl. 245—6)

This invention is a belt including wire coils intermeshed in parallel arrangement. The belt is primarily intended for use as a conveyer and particularly as a furnace conveyer where high 5 temperatures and possible contamination from carried articles are to be expected.

It is well known that a belt of the above character is subject to undue stretching when tensioned, the wire coils functioning as springs 10 which contract. That is to say, tension on the belt must be transmitted from one intermeshed coil to another, by way of their interengaging convolutions, and this transversely tensions the coils so as to transversely stretch their convolutions and cause the coils to shorten. Various 15 schemes have been proposed for remedying this trouble. Some of these accomplish their object but introduce other troubles. For instance, one such scheme is to insert straight wires between 20 the intermeshing portions of the coils in such manner that the ends of these wires bear against the ends of the coils to prevent their contraction and this, although it may prevent stretching, results in the formation of what is essentially a solid mass of metal that dissipates heat 25 very slowly. Also, it results in large bearing surfaces on which the various coils must pivot and thereby introduces undesirable rigidity, particularly when these large surfaces become contaminated. Since the ends of these straight wires 30 bear against the ends of the coils further friction, if not actual interference, is introduced. Another expedient is to relieve the belt of tension by providing it with a carrier but, in this instance, the belt itself does not function as a conveyer, the belt being but a part of an assembly. If the belt is not tensioned, there is obviously no 35 problem involved in its use.

Now one of the objects of the present inventor 40 is to prevent the stretching of belts of the character under discussion without at the same time providing large masses of metal and without interfering with the inherent flexibility of such belts. Other objects may be inferred from the 45 following disclosure of a specific example of a belt embodying the features of the present invention.

This example is illustrated by the accompanying drawing, Figure 1 showing the top of a portion 50 of the same and Figure 2 showing the edge.

The wire coils 1 are shown as being intermeshed in parallel arrangement, the intermeshing of their extreme ends being provided for by interlooped portions 1^a. To prevent the contraction 55 of these coils which is necessary to permit

stretching and which results when they are transversely tensioned while transmitting the longitudinal belt tension, straight wires 2 extend the lengths of alternate ones of the coils, these wires being welded, as at 3, to the convolutions 5 of the coils 1 at positions intermediate their intermeshing portions. It is to be noted that the ends of the wires 2 are in all cases welded to the coils and are free from the interlooped portions 1^a of their ends.

Figure 2 shows that the wires 2 all lie in the same plane, this relationship being maintained throughout the belt. Furthermore, it shows most clearly that the wires 2 are welded to the insides of the convolutions of the coils 1 whereby 15 they are out of the way.

A belt constructed like the disclosed example obviously does not provide excessive masses of metal. As shown by the drawing, the welding may be done electrically whereby the contact 20 between the wires 2 and the coils 1 are essentially of a point character. Although the use of the wires 2 results in additional metal, the large radiation areas provide at the same time for quick heat dissipation. The free character of 25 the ends of the wires 2 is also important in this respect.

Furthermore, the fact that the wires 2 are between the intermeshing portions of the coils 1 allows the belt to flex exactly as though the wires 30 2 were not used at all. That is to say, the frictional surfaces on which the coils 1 must pivot are not increased in area, this being particularly important in furnace work where contamination 35 of the pivoting parts is apt to occur. Here again 35 the importance of the free character of the ends of the wires 2 is to be noted, there being absolutely no interference presented the pivoting action of the interlooped portions 1^a of the coils 1.

The above advantages are so inherent in the 40 present invention that the wires 2 may be arranged in the same plane and on the inside of the coils without the re-introduction of the mentioned troubles. The described positioning of the wires 2 is important in the interests of getting 45 them out of the way and at the same time providing a neat and structurally strong unit.

Although a specific example of this invention has been described in accordance with the patent statutes, it is to be understood that this is 50 not intended as a limitation of the scope of the invention other than as defined by the appended claims.

I claim:

1. A belt having wire coils intermeshed in par- 55

allel arrangement, said belt being adapted to work under tension transmitted transversely through said coils by way of their convolutions and having cross wires extending the lengths of at least some of said coils, each of said cross wires being positioned free from the intermeshing portions of the convolutions of said coils and being fixed to both ends of the coil with which it is associated to prevent contraction of said 10 coil when said belt is tensioned.

2. A belt having wire coils intermeshed in parallel arrangement, said belt being adapted to work under tension transmitted transversely through said coils by way of their convolutions and having cross wires extending the lengths of at least some of said coils, each of said cross wires being positioned free from the intermeshing portions of the convolutions of said coils and being welded to the insides of the convolutions 15

of the coil with which it is associated at both ends of said coil to prevent contraction of the latter when said belt is tensioned.

3. A belt having wire coils intermeshed in parallel arrangement, said belt being adapted to work under tension transmitted transversely through said coils by way of their convolutions and having cross wires extending the lengths of at least some of said coils, each of said cross wires being positioned free from the intermeshing portions of the convolutions of said coils and being welded to the sides of the convolutions of the coil with which it is associated at positions intermediate the portions of said convolutions intermeshing with the convolutions of adjacent 10 coils and at both ends of said coil to prevent contraction of the latter when said belt is tensioned. 15

NOAH S. HARTER.
